UNITED STATES PATENT OFFICE.

KENNETH D. BRYSON, OF NEW YORK, N. Y.

COLLAPSIBLE TUBE.

1,092,691.

Specification of Letters Patent.

Patented Apr. 7, 1914.

Application filed August 14, 1913. Serial No. 784,756.

To all whom it may concern:

Be it known that I, KENNETH D. BRYSON, a citizen of the United States, residing at New York, in the county of New York and 5 State of New York, have invented certain new and useful Improvements in Collapsible Tubes, of which the following is a specification.

My invention relates to collapsible tubes 10 especially designed for the storage and dispensing of pasty or viscous substances, such as tooth paste, cold cream, vaseline, library paste, and the like.

The well known metallic collapsible tube 15 provided with a screw cap closure or pin is familiar to all and though several inventions have been along this line it has many undesirable features, as for instance it is not strictly sanitary on account of crevices, the 20 cap or pin is often dropped when removed from the tube, and if the cap or pin be left off for any appreciable time, the material within the tube becomes hardened and caked at the orifice. Furthermore with the various forms in present use it is impossible 25 to sterilize the tube and contents after it has been filled. In addition when the cap or pin has been removed and the desired amount of the contents squeezed out a certain 30 amount will voluntarily exude therefrom causing annoyance, uncleanliness, and waste.

The object of the present invention is to eliminate the objectionable features of the 35 tubes in present use and to provide a collapsible retainer formed of flexible metal, rubber, or other suitable material and provided with a novel form of discharge nozzle which is opened by pressure upon the container to 40 allow the expeditious and cleanly removal of the required amount of the contents onto a tooth brush, finger, or other desired situation and which will automatically close when the pressure is removed leaving a smooth 45 clean surface without any manual manipulation of the nozzle itself.

A further object is to provide means within the nozzle whereby it may be locked to prevent the accidental discharge of the 50 contents while in transportation or while in a traveling bag or the pocket.

Other objects and advantages such as simplicity, efficiency, durability, and cheapness, will be clearly brought out in the following 55 specification and illustrated in the accompanying drawings, in which:

Figure 1 is a side elevation of my improved tube, the nozzle portion being shown in section, Fig. 2 is a front elevation thereof, Fig. 3 is a cross sectional view on the line 3—3 of Fig. 1, and Fig. 4 is a view similar to Fig. 1, showing a slightly different form of nozzle piston.

Referring more particularly to the drawings, the numeral 1 designates the body of 65 the tube having one end closed as at 2, by crimping, soldering, or in any other well known or preferred manner. The other end of the tube has a thickened portion 3 upon which is formed a projecting nozzle 4 provided with a preferably cylindrical bore 5 within which is disposed for reciprocatory movement a piston 6. At its inner end the piston 6 is provided with a transverse opening 7 through which extends one end 8 of a 70 spring 9 which extends through an opening 10 formed in the thickened portion 3 of the tube. The spring 9 exteriorly of the tube 1 is reflexly bent as at 11 and has its outer end bent to provide a projection 12 disposed 75 within a recess 13 formed in the wall 3. Diametrically opposite to the opening 10 in the tube and in alignment with the end 8 of the spring, is a recess 14 formed in the interior wall of the tube. 80

The piston 6 may be of any desired cross section and provided with any suitable bore for permitting the passage of material therethrough, but I preferably employ a piston having a closed outer end and provided with 90 a peripheral groove 15 extending longitudinally of the piston communicating with the interior of the tube and terminating short of the closed head. 85

The operation of the device is as follows: 95 The tube 1 being filled in the usual manner, the contents may be discharged therefrom by simply pressing upon the closed end of the tube in the customary manner. The pressure will then cause the contents of the tube 100 to be forced against the inner end of the piston 6 and also into the groove or passage 15. This pressure against the inner end of the piston and against the closed head causes the piston 6 to be moved outwardly against 105 the resistance of the spring 9. It will be observed that this outward movement is limited by the end 8 of the spring abutting against the inner face of the portion 3, but is sufficient to allow the outer end of the piston 6 to protrude sufficiently beyond the 110 end of the nozzle 4, as shown by dotted lines

in Fig. 1, to allow the groove or passage 15 to communicate with the exterior of the tube, whereupon the contents of the tube will be forced out. I have shown in Fig. 3, the 5 groove 15 as being semicircular in cross section though it will be understood that it may be formed flat or of any other desired cross section for delivering a thin ribbon of paste if desired.

10 The position of the spring 9, as shown in Fig. 1, is such as to allow the contents to be discharged by simply pressing upon the tube. In order to lock the piston 6 against outward movement to prevent the discharge of the contents, it is simply necessary to press the spring 9 inwardly whereupon the end 8 will pass through the opening 7 in the piston 6 and into the recess 14, as shown in Fig. 4, which will of course prevent movement 15 of the piston. The end 8 of the spring may be pointed if desired, and as shown, in order to facilitate its passage through the material in the tube so that it may easily displace it and seat itself within the recess 14. The 20 recess 13 upon the exterior of the wall 3 being engaged by the bent end 12 of the spring 9 limits the outward movement of the spring when it is pulled outwardly to disengage the end 8 from the recess 14 and 25 also serves as a guide for steadyng the movement of the spring.

25 In Fig. 4 I have shown a slightly modified form of piston. In this form instead of employing a piston provided with a peripheral recess 30 13, as in Fig. 1, I employ a piston 16 which is provided with an opening 17 for the passage of the end 8 of the spring 9 and also provided with a central bore or passage 18 communicating with a laterally extending 35 passage 19 and having a closed outer end. The inner end of the piston 16 is shown beveled, as at 21, in order to obviate the necessity of drilling more than one hole for the passage of the spring. The operation of 40 this form of the device is identically the same as that of the previous form.

Surgeons have heretofore found reason for objecting to the use of the well known types of tubes inasmuch as it is impossible 50 to sterilize the tube and its contents after filling, as, if the ordinary form of tube were subjected to any appreciable heat the contents would expand and burst the tube unless the cap or pin were removed and if the 55 cap or pin were removed the contents of the tube would flow out. With my improved form of tube this sterilization becomes a simple matter as it may be subjected to the required degree of heat without danger of 60 bursting the tube as the expansion of the contents would force merely a certain amount of the contents through the automatically movable piston until the pressure was relieved, whereupon the piston would 65 retract itself.

It will thus be seen that I have provided a collapsible container or tube avoiding objectionable features of the old forms and incorporating many advantages which recommend its use to physicians, surgeons, 70 and all others desiring a sanitary and efficient dispensing tube for surgical, toilet and other preparations.

Having thus described my invention what I claim is:

1. A collapsible tube comprising a pliable shell and a discharge nozzle formed thereon, said nozzle being provided with a closure which is automatically opened by the pressure of the contents of the tube, and means 80 for locking said nozzle when in its closed position.

2. A collapsible tube comprising a pliable shell, a discharge nozzle formed thereon, said nozzle being provided with a closure which is automatically opened by the pressure of the contents of the tube, and releasable means for locking said nozzle when in a closed position.

3. A collapsible tube comprising a pliable shell, a projecting nozzle formed thereon, said nozzle being provided with a closure which is automatically opened by the pressure of the contents of the tube, a spring for normally maintaining said nozzle in its 90 closed position, and means for releasably locking said nozzle when in its closed position.

4. A collapsible tube comprising a pliable shell, a projecting nozzle casing formed thereon, a longitudinally movable piston slidale in said casing, resilient means for holding said piston in its innermost position, and means for locking said piston against movement.

5. A collapsible tube comprising a pliable shell, a projecting nozzle casing formed thereon, a piston longitudinally movable in said casing, a spring engaging said piston for holding it normally in its closed position, and means for locking said piston against movement.

6. A collapsible tube comprising a pliable shell, a projecting nozzle casing formed thereon, a longitudinally reciprocatory piston slidale in said casing and provided with a passage, and a spring extending transversely through said piston and said shell for returning said piston to its closed position.

7. A collapsible tube comprising a pliable shell, a nozzle casing formed thereon, a piston slidale in said casing and provided with a passage, a spring engaging said piston and said shell for holding said piston in its normally closed position, and means for locking said piston against movement.

8. A collapsible tube comprising a pliable shell, a nozzle casing formed thereon, a piston slidale in said casing and provided with

a passage, and a spring extending through said piston and said shell, said spring being movable to engage a recess for preventing movement of said piston.

- 5 9. A collapsible tube comprising a pliable shell, a nozzle casing formed thereon, a piston longitudinally slidble in said casing, said casing being provided with a recess upon its outer end, and said shell being provided with a recess upon its inner periphery, and a spring extending through said shell and said piston, said spring being provided with a bent portion in engagement with said first named recess and said spring being movable into engagement with said second named recess for preventing movement of said piston.
- 10 15. A collapsible tube comprising a pliable shell, a nozzle casing thereon, a piston slid-

able in said casing and provided with a passage for the passage of the contents of said shell to the exterior thereof when pressure is applied thereto, a recess in the outer end of said casing, a recess in the inner periphery of said shell, and a spring extending through said shell and said piston, said spring being provided with a bent portion in engagement with said first named recess and being movable into engagement with said second named recess for preventing accidental movement of said piston.

In testimony whereof I hereto affix my signature in the presence of two witnesses.

KENNETH D. BRYSON.
